UNITED STATES PATENT OFFICE

LÉON CRAYSSAC, OF SETE, FRANCE

PRESS FOR OBTAINING PHOTOGRAPHIC PRINTS BY MEANS OF ELECTRIC LIGHT.

Application filed October 20, 1928, Serial No. 313,819, and in France October 27, 1927.

The present invention relates to an apparatus for obtaining photographic prints, the purpose being to make a handy light tight apparatus of reduced proportions with the possibility of using the ordinary electric light current, with the secondary purpose to be useful in developing by red light. These results are obtainable by the apparatus according to the invention, which comprises a casing closed by a cover having a lid or platen linked or hinged thereto, a frame being movably arranged in this casing under said lid and resting on members pressing upwardly such as springs or eccentrics, said platen 10 pressing upon a transparent panel, shutting off the frame on its upper side and carrying a margin plate with an opening window corresponding to the dimensions of the print to be obtained within the margin lines. The cover 15 is provided with an edge or border under the shutter, projecting over the frame and having a lateral stop for the purpose of adjusting the margin plate independently of the frame in always the same position.

20 The drawings show a preferred embodiment of the invention.

Referring to the drawings:

Fig. 1 is a perspective view of a photographic printing and developing apparatus 30 according to the invention.

Fig. 2 shows a detail of an internal part of the printing and developing apparatus.

Fig. 3 is a side view of the inside of the apparatus.

35 Fig. 4 is a vertical section through the back wall which is provided with ventilation chimneys.

Fig. 5 is a perspective view of the upper part of the apparatus in the open position.

40 Fig. 6 shows a vertical section through the part shown in Fig. 5 which contains a plurality of opal glasses.

Fig. 7 is a vertical section of Fig. 6.

45 Fig. 8 is a front view corresponding to Fig. 6 showing the negative inserted in position.

Fig. 9 is a vertical section of Fig. 8, similar to Fig. 7.

50 Fig. 10 shows a perspective view of the up-

per part as shown in Fig. 5 ready to receive the negative print, film or glass plate.

Fig. 11 shows a modification of the lifting means of the frame in the casing.

The printing and developing apparatus 55 according to the invention consists of a casing 1, provided on its upper part with a rheostat or electric resistance 2 and a switch 3 (Figs. 1, 2 and 3) controlling an incandescent electric lamp 4 for white light and an incandescent electric lamp 5 for red light. A cable or wire 6 leads the electric current into the casing to the lamps. The switch 3 renders it possible to expose either to nonactinic red light, or to actinic white light; the resistance 2 renders it possible to diminish the intensity of the white light according to the degree of transparency of the negative for obtaining a copy of the kind desired. The lamp 4 is fixed onto a slide 7 slidably within guides 8 and 9 (Fig. 2). The position of the slide within the casing 1 can be changed by means of cords or strings 10 and 11 which pass through the side walls of the casing 1. The purpose of changing the position of the lamp 4 is to weaken the contours given by the margin plate on the negative print.

In the lower part of the casing 1 is a drawer 12 having two or more compartments for receiving the copies after exposure or the papers for copies before exposure. A ceiling 13 prevents light from penetrating into the drawer 12. The latter touches a vertical wall 14 between the bottom of the casing and the ceiling 13, thus leaving a space for ventilation by means of openings 17 and 18 (Fig. 4). In the upper part of the back wall is an exhaust opening 19 for warm air which is protected by a chimney against the passage of light through it.

90 Wires 15 and 16 conduct electric current to the lamp and permit moving the slide 7.

A red window 21 at the side of the casing 1 enables the apparatus to be used as a red lantern during the development of prints. Hinges 24 provided on a lid or platen 22 render it possible to open the cover. The said platen 22 is lined or clothed with felt 25. The upper part of the front wall adjacent to the platen 22 can be opened by means 100

of hinges 38, 39 (Fig. 5) and is provided with a projecting spring 26, which by means of its nose 27 keeps the platen 22 closed. Below the closed platen 22 is a movable frame 28, 29 provided with horizontal rails 30, 31, 32 for carrying opal glasses, glass plates or margin plates and the like (33, 34, 35 in Figs. 5 to 9). The side walls 28, 29 of this frame are fixed to a back wall 36 (Figs. 7 and 9) and kept together at the lower part of their front side by a metallic bar 37. For putting opal glasses 33, 34, 35 into the frame the hinged cover of the front wall is laid down as shown in Fig. 5 by lifting up two hooks 40 from their pins 41 fixed to this upper lid. For reinforcement purposes, the flat spring 26 is arranged so as to form one half of a hinge, the other half being fixed to the lower part of the front wall, thus transferring the strain into the half 42 of the hinge, i. e. to said lower part of the front wall of the casing 1.

Each side wall 28 and 29 of the frame rests on a metallic spring 43 and 44 respectively carried by two rails 45 and 46 mounted on two wooden borders or rims 47, 48 on the side walls of the casing. The rails 45, 46 facilitate the sliding of the springs 43, 44 when the frame 28, 29, 36, 37 is pressed downwards.

The back wall 36 of the frame is guided by a vertical wall 49 within the casing. A transparent panel 50 rests on the top of said frame, and carries an interchangeable metallic margin cover 51 having an opening corresponding to the dimensions of the print to be obtained or to the dimensions of the negative print respectively. The upper edge of the front hinged cover is provided with a thin metallic border or rim 52 projecting in such a manner as to prevent the front edge of the margin plate on the panel 50 and the frame 28, 29 from rising. A small portion of the back part of the frame meets with the under side of the cover adjacent to the platen 22, said underside being also provided along its whole length with a small projecting rim 53. In closed position the shutter 22 presses the frame 28, 29 slightly downwards so as to hold the sensitive paper with the necessary pressure against the negative, even if the negative is only a thin film.

The frame 28, 29 is guided by pins 54, 55 vertically movable in guiding slits 56, 57. These pins are connected to a bridge member or stirrup 61 by wires 59 and 60, said stirrup surrounding partially the casing 1, and being pivotally mounted in the side walls of said casing and being furthermore provided with a handle 62 at the front side for the purpose of lowering easily the frame 28, 29 within the interior of the casing, if a negative 63 (glass or film) has to be introduced under the metallic rail 53 (Figs. 8 and 9). This having been done the margin plate is put

onto the negative in such a manner as to leave uncovered only those parts which are to be copied. The handle 62 is then released. The frame rises and the negative is kept immovable between glass panel and rim 53. The negative is adjusted in this manner for any number of copies not only by the immovable part of the cover, that is, its edge 64, but also by a lateral stop 65 perpendicular to said edge. Said stop passes into a slit provided on the platen 22 when the same is closed (Fig. 5). In this manner an equal margin on all copies will be obtained.

If it is necessary to avoid copying some parts, such parts must be covered and for this purpose more or less transparent covering frames are placed on the plates 33, 34, 35. These frames can easily be adjusted with accuracy after switching in the white lamp 4, because it is possible to look through the negative to check the right position and the effect produced by the covering frames which have been introduced.

The intensity of the lamp is then regulated according to the transparency of the negative glass plate or the film and according to the sensitiveness of the sensitive paper. When this has been done the red lamp 5 is lighted, the lamp 4 being at the same time automatically extinguished. The sensitive paper is then introduced, the platen 22 is closed and the red light changed to white light by actuating the switch 3. During the exposure the white lamp may be displaced by means of the cords 10 and 11 in order to weaken the contours of the margin plates on the copy. After exposure the red light is again lighted and the sensitive paper is changed. When all the copies have been made, the apparatus is used as a red lantern by lighting either the white lamp 4 or the red one 5 according to the sensitiveness of the paper exposed.

As shown in Fig. 11 the frames 28, 29 could also be lifted up or raised by means of eccentrics 70 to be actuated from the outside of the casing for pressing the frame on to the shutter 22 after closing. The frame may rest directly on said eccentrics or indirectly by inserting a metallic strip 71 between eccentrics and frame.

The casing is light-tight, the apparatus very simple, having no pegs but only a simple lever for lowering the frame. The margin plates can easily be removed or exchanged after having opened the front shutter, because only the uppermost margin plate is held at its front part by the rim 52 of the front shutter.

I claim:

1. In an apparatus for obtaining photographic prints, the combination of: a light-tight casing, a cover on said casing, illuminating means arranged within said casing, a frame arranged above said illuminating

- means so as to be slidable within said casing, a platen forming part of said cover and adapted to cover the upper part of said frame, a transparent panel on the top of said frame upon which panel the negative is placed, a rim fixed to said cover located below the platen and projecting over said frame, a hinged front on said casing, a rim on said hinged front and means for pressing said frame upwards towards said rims in such manner as to hold both the negative and said panel firmly in position between said frame and said rims even during the changing of the print. 10
- 15 2. In an apparatus for obtaining photographic prints, a combination as specified in claim 1, wherein said frame is connected with external means for moving it.
3. In an apparatus for obtaining photographic prints, a combination as specified in claim 1 in further combination with pins arranged on said frame and passing through vertical slits in said casing, and means connected to said device and adapted to move 20 said frame.
- 25 4. In an apparatus for obtaining photographic prints, a combination as specified in claim 1, in further combination with a lateral stop on said cover for adjusting the position of the positive, the negative and said panel.
- 30 5. In an apparatus for obtaining photographic prints, the combination of a light tight casing, an electric lamp therein, means for shifting said lamp, a frame arranged above said lamp and slidable in said casing, a platen forming part of the cover of said casing and covering the top part of said frame, a transparent panel on the top of said 35 frame, means for raising the frame and pressing the latter upwardly against the platen, a rim fixed to the cover along the side adjacent to the platen lying under the platen and projecting over the frame, a lateral stop for adjusting a negative independently of the frame, a hinged front on said casing, a rim on said hinged front projecting over the transparent panel, and means for keeping both the platen and the hinged front in closed 40 position.
- 45 6. In an apparatus for obtaining photographic prints the combination of a light tight casing, a cover on said casing, an electric circuit within said casing containing an electric white light and an electric red light, a switch for lighting and interchanging the white or the red light and an electric resistance for graduating the lighting effect, means for moving the white light to and fro, a frame arranged above said lights and slid- 50 able in said casing, a platen forming part of the cover of said casing and covering the top of said frame, a margin plate on the top of said frame, a panel under said margin plate, means for raising said frame and press- 55
